IRRIGATION PUMP

Holger Adolf Edvard Johnsen, Fort Lauderdale,
Fla., assignor of one-half to J. B. Fraser, Fort
Lauderdale, Fla.

Application September 9, 1940, Serial No. 356,056

4 Claims.

(Cl. 103—3)

The present invention relates generally to a pumping mechanism, and more particularly to an irrigation and drainage pump.

An object of the invention is the provision of an irrigation pump having reversible pumping mechanism whereby the device may be used to pump water either from an irrigation canal to a field to be irrigated, or from a flooded field to a canal, depending upon the condition of the fields adjacent the pump.

Another object is to provide a reversible pump of this character having an inlet port located at a higher level than the outlet port, in combination with a drive shaft extending longitudinally of the pump casing and having at its lower end a propeller positioned between the inlet and outlet ports. The upper portion of the shaft is journaled in thrust bearings. With such a construction, liquid forced downwardly from the upper inlet port to the lower outlet port will cause a reaction upwardly against the propeller and effect an upward thrust on the shaft, thus compensating for the weight of the shaft on the upper thrust bearings.

A further object is the provision of a simple and effective bearing for the lower end of the reversible pump casing in the pump housing. This bearing consists of a raised section at the lower end of the pump housing, the top portion of which is flat for receiving the lower end of the reversible mechanism.

Another object is to provide the pump housing with a fin or sealing wall extending around the bottom and opposite walls of the housing and located between the inlet and outlet ports of the pump. This fin is preferably extended beyond the limits of the usual sump within which the pump is positioned, so as to form a seal to prevent return of the water from the outlet to the inlet side of the pump.

With the foregoing and other objects in view, the invention will now be more particularly described, reference being had to the accompanying drawing, in which the figure is a section taken longitudinally of the pump.

Referring now to the drawing, the numeral 10 designates generally an irrigation pump constituting the subject matter of the present invention. This pump, while capable of varied use, is primarily designed as an irrigation pump for use in land where it is desired to pump water or other liquid from an irrigation canal to one or more fields which are to be irrigated. In actual use, the pump is designed to be positioned within a sump which is located between the field

being irrigated and the canal or other supply of water usually located at a lower level than the field. The bottom of the sump and the lower end of the pump should always be below the water level of the canal.

The pump 10 comprises an outer housing 11 of substantially cylindrical formation. This housing may be formed of any desired number of parts or sections. The lower end of this housing 10 is provided with a pair of aligned outlet ports 12 and 13, each port being associated with a flanged collar 14. The housing 11 is also provided, at a point above the outlet ports 12 and 13, with a pair of aligned inlet ports 15 and 16 extending in the same direction as the ports 12 and 13.

Within the housing 11 is rotatably mounted a pump casing 17. This casing comprises a lower valve section 18 and an upper shaft supporting section 19. The lower portion 18 is of greater diameter than the section 19 and, as shown in the drawing, has a relatively close fit with the inner walls of the housing 11. The extreme lower end 20 of the section 18 rests upon a flat central bearing portion 21 of a raised element 22 supported upon the bottom wall 23 of the housing 11. The element 22 is provided with oppositely inclined walls 24 and 25 which connect with the flat bearing portion 21. The whole element 22 constitutes a ridge or partition which cooperates with the lower end of the casing section 18 to divert the flow of fluid through either of the outlet ports 12 or 13, as will be described in detail hereinafter.

As will be observed, the lower end 20 of the section 18 extends over substantially one-half of the area of the bottom of the housing 11. This end portion 20 is of sufficient area, however, to extend over and rest upon the flat bearing portion 21, as clearly shown in the drawing. The lower side wall of the section 18 is cut away to provide a port 26 which is adapted to communicate with either of the outlet ports 12 and 13. It will be observed that the curved side walls of the port 26 connect at their lower ends with the inward extension of the lower end section 20. Since the flow of water will be downwardly through the port 26, there is provided an inclined deflecting plate 27 which extends from the inner end of the portion 20 upwardly to a point where it connects with the cylindrical wall of the lower section 18. This lower section 18 also has formed therein an inlet port 28 located above the outlet port 26 and adapted to register with

one or the other of the ports 15 and 16 of the housing 11.

The enlarged cylindrical portion of this lower section 18 terminates at a point above the inlet ports 15 and 16, and at this point is secured to a horizontal plate 29 constituting a shaft bearing support. This plate also supports a cylindrical shaft housing 30 which extends to the top of the pump and is connected to a top plate 31 having a flange 32 which rests upon and is rotatable relative to a flange 33 of the top of the pump housing 11. It is to be understood that the elements 18, 29, 30 and 31 are all fixed to each other so that these elements may be rotated as a unit within the housing 11 when it is desired to reverse the pump, as will be hereinafter described.

Extending longitudinally of and journaled in the pump casing is a drive shaft 34. This shaft is journaled in thrust bearings 35 mounted in the upper portion of the shaft housing 30. The lower portion of the shaft is journaled in suitable bearings 36 carried by the plate 29. In order to insure against the leakage of fluid from either above or below the bearing 36, I provide a rubber bearing 37 supported by the plate 29.

Upon the extreme lower end of the shaft 34 is mounted a propeller 38. It will be observed that this propeller is confined within a portion of the lower section 18 between the ports 26 and 28. That is, the propeller is mounted below the port 28 and above the port 26. The upper end of the shaft may be connected to any suitable power means for effectively driving the shaft and propeller. In the present instance, there is disclosed a sprocket wheel 39, fixed to the upper end of the shaft, and a sprocket chain 40.

Flap valves 41 and 42 are provided to close the ports 12 and 13, respectively. Each valve is pivotally connected to a supporting arm 43, the upper end of which is pivotally connected to a bracket 44 fixed to the outer wall of the housing 11. Normally, each valve will be closed by gravity but is free to swing outwardly by reason of the flow of water passing through its respective outlet port.

In use of the device, and assuming that it is desired to pump water from an irrigation canal to a field to be irrigated, the several ports are located in the position shown in the drawing. The propeller is always rotated in a direction to induce a downward current of water or other fluid. Thus, the flow of water will be through the inlet ports 16 and 28 which are in register, down through the interior of the lower section 18 of the pump casing, and then outwardly through the aligned ports 26 and 12. The force of the water passing through the port 12 will raise the flap valve 41, so that the flow of the water will be unrestricted from the irrigation canal to the field to be irrigated.

If the conditions should be such that a field has been flooded to such an extent where the crops would become damaged if the water is not drawn off from the field, this contingency may be taken care of by reversing the pump mechanism in the housing 11. For this purpose, a handle 45 is provided, the inner end of which is rigidly connected to the top plate 31 of the pump casing. By moving the handle 45, the pump casing may be rotated within the housing 11 so that the inlet port 28 will register with the inlet port 15 and the outlet port 26 register with the outlet port 13. Thereafter, upon operation of the propeller, the flow of fluid will be reversed,

and the flooded field may be easily and quickly drained of the excessive water, which will be pumped back into the irrigation canal.

In order to insure that the water being pumped from one side of the sump will not return to the inlet side of the pump, I provide a sealing fin 46. This fin is of substantially channel-shaped formation in cross section, comprising a base 47 which is rigidly connected to the pump housing 11 and the spaced walls 48 extending outwardly from the base. This fin, as shown in the drawing, extends across the bottom of the housing 11, and upwardly upon opposite sides of the housing to a point at least above the high water line of the sump. The fin is positioned between the inlet and outlet ports and preferably extends beyond the walls or limitations of the sump within which the pump is located, thereby providing an effective seal between the inlet and outlet sides of the pump and insuring against return of the water from the outlet to the inlet side of the pump.

While I have shown and described a pump construction in which there is only one reversible inlet and outlet, it is to be understood that, if desired, a plurality of inlet and outlet ports may be provided to radiate at different angles. With this arrangement, and by use of suitable piping, a single pump may be utilized for connecting one of a plurality of irrigation canals with one of a plurality of fields.

It is to be further understood that the construction shown and described is merely illustrative of a preferred embodiment and that such changes may be made as fall within the purview of one skilled in the art, without departing from the spirit of the invention and the scope of the appended claims.

I claim:

1. In an irrigation pump, a housing of substantially cylindrical formation having a pair of oppositely disposed outlet ports adjacent its lower end, said housing having a pair of opposed inlet ports located above said outlet ports, a substantially cylindrical pump casing rotatably mounted in said housing, with its lower portion having a close fit with the walls of the housing, said pump casing having a lower outlet port registrable with either of said housing outlet ports, the portion of said pump casing opposite its outlet port being imperforate and closing one outlet port of the housing when the other housing outlet port is in register with the outlet port of the pump casing, said pump casing having an upper inlet port registrable with either of said housing inlet ports, the portion of said pump casing opposite its inlet port being imperforate and closing one inlet port of the housing when the other housing inlet port is in register with the inlet port of the pump casing, a drive shaft journaled in and longitudinally of the pump casing, a driven flow producing means mounted on said shaft between the inlet and outlet ports, and means associated with the pump casing for rotating said casing to reverse the position of the casing inlet and outlet ports and thereby reverse the flow through the pump.

2. In an irrigation pump, a housing of substantially cylindrical formation having a pair of oppositely disposed outlet ports adjacent its lower end, said housing having a pair of opposed inlet ports located above said outlet ports, a substantially cylindrical pump casing rotatably mounted in said housing, with its lower portion having a close fit with the walls of the housing, said pump

casing having a lower outlet port registerable with either of said housing outlet ports, the portion of said pump casing opposite its outlet port being imperforate and closing one outlet port of the housing when the other housing outlet port is in register with the outlet port of the pump casing, said pump casing having an upper inlet port registerable with either of said housing inlet ports, the portion of said pump casing opposite its inlet port being imperforate and closing one inlet port of the housing when the other housing inlet port is in register with the inlet port of the pump casing, a drive shaft journaled in and longitudinally of the pump casing, the bearing means for said shaft including thrust bearings carried by said pump casing adjacent the top of said casing, a propeller mounted on the lower end of said shaft between the inlet and outlet ports, and means carried at the upper end of said pump casing above the thrust bearings for rotating said casing to reverse the position of the casing inlet and outlet ports and thereby reverse the flow through the pump.

3. In an irrigation pump, a housing of substantially cylindrical formation having a pair of oppositely disposed outlet ports adjacent its lower end, said housing having a pair of opposed inlet ports located above said outlet ports, the lower end of said housing having a raised partition extending across the interior thereof, the top of said raised portion being flat and constituting a lower bearing surface, a substantially cylindrical pump casing rotatably mounted in said housing, with its lower portion having a close fit with the walls of the housing and its lower end supported upon the flat top of the raised portion of the housing, said pump casing having a lower outlet port registerable with either of said housing outlet ports, the portion of said pump casing opposite its outlet port being imperforate and closing one outlet port of the housing when the other

housing outlet port is in register with the outlet port of the pump casing, said pump casing having an upper inlet port registerable with either of said housing inlet ports, the portion of said pump casing opposite its inlet port being imperforate and closing one inlet port of the housing when the other housing inlet port is in register with the inlet port of the pump casing, a drive shaft journaled in and longitudinally of the pump casing, a driven flow producing means mounted on said shaft between the inlet and outlet ports, and means carried by said pump casing for rotating said casing to reverse the position of the casing inlet and outlet ports and thereby reverse the flow through the pump.

4. In an irrigation pump, a housing of substantially cylindrical formation having a plurality of outlet ports, said housing having a plurality of inlet ports located above said outlet ports, a pump casing rotatably mounted in said housing, said pump casing having a lower outlet port registerable with each of said housing outlet ports, the portion of said pump casing in the same horizontal area as its outlet port being imperforate so that flow could only occur to one outlet port of said housing in any flow position of the casing, said pump casing having an upper inlet port registerable with each of said housing inlet ports, the portion of said pump casing in the same horizontal area as its inlet port being imperforate so that flow could only occur to one inlet port of said housing in any flow position of the casing, a drive shaft journaled in the pump casing, a driven flow producing means mounted on said shaft between the inlet and outlet ports, and means associated with the pump casing for rotating said casing to change the positions of the casing inlet and outlet ports and thereby change the direction of flow through the pump.
